COMBINED TARGET AND GAME BOARD

Norbert Zielinski, 2622 S. Ridgeway Ave.,
Chicago, Ill. 60623

Filed Jan. 11, 1968, Ser. No. 10,129

Term of patent 14 years

U.S. Cl. D34—5
Int. Cl. D21—01

FIG. 1

FIG. 2

FIG. 3

FIG. 4

FIG. 1 is a front elevational view of a combined target and game board showing my new design;

FIG. 2 is a rear elevational view of the combined target and game board of FIG. 1;

FIG. 3 is an end elevational view of the left hand end of the combined target and game board of FIG. 1; and

FIG. 4 is a plan view of the combined target and game board of FIG. 1.

I claim:

The ornamental design for a combined target and game board, substantially as shown and described.
